ABSTRACT OF THE DISCLOSURE

A forced circulation steam generator having a furnace wall structure comprising a pair of parallel flow through-flow paths, each path including a group of tube panels, each tube panel having a multiplicity of parallel flow tubes, with tubes of the panels of each path being interlaced with and rigidly united to tubes of the panels of the other path. Provisions are made for supplying fluid in parallel flow relation to the paths and for interconnecting the tube panels of each path so as to provide serial flow of fluid therethrough and so that with respect to the longitudinal edges of the wall structure the general direction of flow of fluid in one path is opposite to the general direction of flow of fluid in the other path.

The present invention relates to improvements in the construction and arrangement of fluid heating circuits especially adapted for use in a forced circulation once-through steam generating unit.

The construction of a modern forced circulation once-through steam generator requires the use of a large number of parallel flow circuits connected between inlet and outlet headers and the provision of a furnace having gas-impermeable boundary walls formed by rigidly united tubes. One of the fundamental problems involved with such a steam generator is the control of the flow through the various parallel flow circuits over the operating load range in order that the flow in each circuit will be stable and the enthalpy of the fluid discharged from any individual circuit will be close to the average of that from all circuits, in which case the circuit will be in a balanced flow condition. Unbalanced flow may be caused by unequal heat absorption in parallel flow circuits due to an unsymmetrical arrangement of heating surface, slag accumulation, or part-load operation with burners out of service; or may be due to unequal resistances caused by different lengths of circuits. When steam or water, or mixtures thereof, is heated in parallel flow paths provided by the furnace wall tubes or tubular panels disposed in the furnace, unbalanced heat and/or fluid distribution may lead to excessive localized tube metal temperatures and/or to excessive temperature differentials between adjacent furnace wall tubes and, thereby, to undue thermal stresses in the furnace wall-forming components.

Many variations of furnace wall fluid heating circuitry have been applied to vapor generators of the character described. Most of these have one or more shortcomings including excessive thermal stresses, uneven thermal expansion, and/or lack of sufficient stability against transient conditions of heat absorption inherent in the operation of a vapor generator of the character described.

The present invention solves the foregoing problems by subdividing the furnace boundary walls into a plurality of specially arranged fluid heating paths. In accordance with the invention, in a unit of the character described each upright boundary wall of the furnace comprises a pair of parallel flow through-flow paths, each path including first and second groups of tube panels, each tube panel including a multiplicity of parallel flow tubes. Tubes

of the panels of the first group in each path are juxtaposed with tubes of the panels of the first group of the other path and cooperate therewith to form a lower portion of the wall structure, while tubes of the panels of the second group of said one path are juxtaposed with tubes of the panels of the second group of the other path and cooperate therewith to form an upper portion of the wall structure. Provisions are made for interconnecting the tube panels of the first and second groups of each path so as to provide serial flow of fluid successively through the tube panels of the first group and the tube panels of the second group and so that with respect to the longitudinal edges of the wall structure the general direction of flow of fluid in said one path in either the upper or lower portion of the wall is contrary to the general direction of fluid in the other path in the corresponding wall portion.

The various features of novelty which characterize the invention are pointed out with particularity in the claims annexed to and forming a part of this specification. For a better understanding of the invention, its operating advantages and specific objects attained by its use, reference should be had to the accompanying drawings and descriptive matter in which there is illustrated and described a preferred embodiment of the invention.

Of the drawings:

FIG. 1 is a diagrammatic view showing a furnace wall of a forced flow once-through steam generator constructed in accordance with the invention; and

FIG. 2 is a side view corresponding to FIG. 1.

In accordance with the invention, the furnace boundary wall fluid heating surface should be so proportioned and arranged that the temperature of the fluid in any tube at any furnace level differs no more than a predetermined amount from the average fluid temperature of all furnace wall tubes at that level; that the maximum temperature differential between adjacent tubes is below a predetermined critical limit; that fluid flow unbalances are minimized; and that the tubes of each fluid heating pass are sufficient in number and in inside diameter along their lengths to provide adequate circulation velocities.

The structure of the drawings is intended for use as one of the upright boundary walls of a forced flow steam generator. The wall structure comprises a pair of parallel flow through-flow paths A and B. Path A includes a first group of upright coplanar tube panels A₁, A₂, A₃, and A₄ each having a multiplicity of upright parallel tubes 10 extending between inlet and outlet headers 12 and 14; while path B includes a first group of upright coplanar tube panels B₁, B₂, B₃, and B₄ each having a multiplicity of upright parallel tubes 16 extending between inlet and outlet headers 18 and 20. Tubes 16 are disposed in the spaces between tubes 10, with tubes 10 and 16 being rigidly united, such as by metallic webs closing the intertube spaces and weld-united to the tubes, to form the lower portion of the wall structure. Headers 12 and 14 of panels A₁ and A₂ are disposed somewhat below the corresponding headers of panels A₃ and A₄, while headers 18 and 20 of panels B₁ and B₂ are located somewhat below the corresponding headers of panels B₃ and B₄, with inlet headers of panels A₁, A₂, B₁, B₂, inlet headers of panels A₃, A₄, B₃, B₄, outlet headers of panels A₁, A₂, B₁, B₂, and outlet headers of panels A₃, A₄, B₃, B₄ being respectively situated at common elevations.

Path A also comprises a second group of upright coplanar tube panels A₅, A₆, A₇ and A₈ each having a multiplicity of upwardly extending parallel tubes 24 extending between inlet and outlet headers 26 and 28 disposed exteriorly of the wall; while path B additionally includes a second group of upright coplanar tube panels B₅, B₆, B₇ and B₈ each having a plurality of upright parallel tubes

30 extending between inlet and outlet headers 32 and 34. Tubes 30 are disposed in the spaces between tubes 24, with tubes 30 and 24 being rigidly united in the same manner as tubes 10 and 16 to form the upper portion of the wall structure. Headers 26 and 28 of panels A₅ and A₆ are situated somewhat below the corresponding headers of panels A₇ and A₈; and headers 32 and 34 of panels B₅ and B₆ are positioned somewhat below the corresponding headers of panels B₇ and B₈. Inlet headers of panels A₅, A₆, B₅, B₆, inlet headers of panels A₇, A₈, B₇, B₈, outlet headers of panels A₅, A₆, B₅, B₆, and outlet headers of panels A₇, A₈, B₇, B₈ are respectively situated at common elevations, with the inlet headers of panels A₅, A₆, B₅, B₆ being situated intermediate outlet headers of panels A₁, A₂, B₁, B₂ and outlet headers of panels A₃, A₄, B₃, B₄. All of the tube panel inlet and outlet headers are so situated as not to be exposed to the high temperature heating gases. Panels A₁, B₄, A₂, B₃, A₃, B₂, A₄ and B₁ are respectively aligned with panels B₅, A₈, B₆, A₇, B₇, A₆, B₈ and A₅. With the panels thus arranged, tubes 10 of panels A₃ and A₄ have upper portions interlaced with lower portions of tubes 24 of panels A₅ and A₆, while tubes 16 of panels B₃ and B₄ have upper portions interlaced with lower portions of tubes 30 of panels B₅ and B₆, with the tube portions so interlaced being rigidly united to form an intermediate portion of the wall structure.

The interconnection of tube panels of fluid flow paths A and B are respectively provided by conduits 36 and 38, each of such conduits being disposed exteriorly of the wall and leading from a panel outlet header to the inlet header of the next adjacent panel of the corresponding flow path. Parallel flow paths A and B are respectively supplied with high pressure fluid by conduits 40 and 42, which lead from a common source, and discharge to other fluid heating circuitry, not shown, by way of conduits 44 and 46. The height of the tube panels of each path is set so that in the event of unbalanced heat and/or fluid flow the temperature of the fluid leaving any tube of a panel is no greater than a predetermined amount above the average temperature of the fluid leaving the corresponding panel to prevent the possibility of undue thermal stresses between laterally adjacent tubes. Each of the conduits 40 and 42 is provided with a throttle valve 48 to assist in neutralizing the effects of unbalances in heat and/or fluid flow.

In operation high pressure fluid is passed in parallel flow relation to flow paths A and B, with the fluid in path A successively passing through panels A₁, A₂, A₃, A₄, A₅, A₆, A₇ and A₈, and the fluid in path B successively passing through panels B₁, B₂, B₃, B₄, B₅, B₆, B₇ and B₈. Along each flow path the outflow of each tube panel is collected in the corresponding outlet header, and then mixed in the corresponding conduit 36 or 38 while passing to the inlet header of the next panel in the flow path. With respect to the longitudinal edges of the wall structure, the general direction of flow of fluid in path A in either the upper or lower portion of the wall is opposite to the general direction of flow of fluid in path B in the corresponding wall portion. Thus the flow of fluid in path A is generally from left to right in the lower portion of the wall and from right to left in the upper portion of the wall, while the flow in path B is from right to left in the lower portion of the wall and from left to right in the upper portion of the wall. With the tube panels of the respective flow paths arranged and interconnected as above described, the temperature of the fluid in any tube at any furnace level will differ no more than a predetermined safe amount from the average fluid temperature of all furnace wall tubes at that level and the maximum temperature differential between adjacent tubes will be below a predetermined critical limit, thereby maintaining differential expansions in the walls within safe limits.

What is claimed is:

1. In a forced circulation fluid heating unit, a wall

structure subject to high temperature heating gases comprising a pair of parallel flow through-flow paths, each path comprising a group of tube panels, each tube panel including a multiplicity of parallel flow tubes, tubes of the panels of each path being interlaced with and rigidly united to tubes of the panels of the other path, means for supplying fluid in parallel flow relation to said paths, means interconnecting the tube panels of each path so as to provide serial flow of fluid therethrough and so that with respect to the longitudinal edges of the wall structure the general direction of flow of fluid in said one path is opposite to the general direction of flow of fluid in said other path.

2. In a forced circulation fluid heating unit, a wall structure subject to high temperature heating gases comprising a pair of parallel flow through-flow paths, each path comprising a group of tube panels, each tube panel including a multiplicity of upflow tubes arranged for parallel flow of fluid therethrough, tubes of the panels of each path being interlaced with and rigidly united to tubes of the panels of the other path, means for supplying fluid in parallel flow relation to said paths, means interconnecting the tube panels of each path so as to provide serial flow of fluid therethrough and so that with respect to the longitudinal edges of the wall structure the general direction of flow of fluid in said one path is contrary to the general direction of flow of fluid in said other path.

3. In a forced circulation fluid heating unit, a wall structure subject to high temperature heating gases comprising a pair of parallel flow through-flow paths, each path comprising first and second groups of tube panels, each tube panel including a multiplicity of parallel flow tubes, tubes of the panels of the first group of each path being juxtaposed with tubes of the panels of the first group of the other path and cooperating therewith to form a lower portion of the wall structure, tubes of the panels of the second group of said one path being juxtaposed with tubes of the panels of the second group of the other path and cooperating therewith to form an upper portion of the wall structure, means for supplying fluid in parallel flow relation to said paths, means interconnecting the tube panels of the first and second groups of each path so as to provide serial flow of fluid successively through the tube panels of the first group and the tube panels of the second group and so that with respect to the longitudinal edges of the wall structure the general direction of flow of fluid in said one path in either the upper or lower portion of the wall is opposite to the general direction of flow of fluid in said other path in the corresponding wall portion.

4. In a forced circulation fluid heating unit, a wall structure subject to high temperature heating gases comprising a pair of parallel flow through-flow paths, each path comprising first and second groups of tube panels, each tube panel including a multiplicity of parallel flow tubes, tubes of the panels of the first group of each path being interlaced with and rigidly united to tubes of the panels of the first group of the other path and cooperating therewith to form a lower portion of the wall structure, tubes of the panels of the second group of said one path being interlaced with and rigidly united to tubes of the panels of the second group of the other path and cooperating therewith to form an upper portion of the wall structure, means for supplying fluid in parallel flow relation to said paths, means interconnecting the tube panels of the first and second groups of each path so as to provide serial flow of fluid successively through the tube panels of the first group and the tube panels of the second group and so that with respect to the longitudinal edges of the wall structure the general direction of flow of fluid in said one path in either the upper or lower portion of the wall is opposite to the general direction of flow of fluid in said other path in the corresponding wall portion.

5. In a forced circulation fluid heating unit, a wall subject to high temperature heating gases comprising a pair of parallel flow through-flow paths, each path com-

prising first and second groups of upflow tube panels, each tube panel including a multiplicity of parallel flow tubes, tubes of the panels of the first group of each path being interlaced with and rigidly united to tubes of the panels of the first group of the other path and cooperating therewith to form a lower portion of the wall structure, tubes of the panels of the second group of said one path being interlaced with and rigidly united to tubes of the panels of the second group of the other path and cooperating therewith to form an upper portion of the wall structure, tube panels of the first group of said one path being aligned with the tube panels of the second group of the other path, tube panels of the second group of said one path being aligned with tube panels of the first group of the other path, means for supplying fluid in parallel flow relation to said paths, means interconnecting the tube panels of the first and second groups of each path so as to provide serial flow of fluid successively through the tube panels of the first group and the tube panels of the second group and so that with respect to the longitudinal edges of the wall structure the general direction of flow of fluid in said one path in either the upper or lower portion of the wall is opposite to the general direction of flow of fluid in said other path in the corresponding wall portion.

6. In a forced circulation fluid heating unit, a wall structure subject to high temperature heating gases comprising a pair of parallel flow through-flow paths, each path comprising first and second groups of upflow tube panels, each tube panel including a multiplicity of parallel flow tubes, tubes of the panels of the first group of each path being interlaced with and rigidly united to tubes

of the panels of the first group of the other path and cooperating therewith to form a lower portion of the wall structure, tubes of the panels of the second group of said one path being interlaced with and rigidly united to tubes of the panels of the second group of the other path and cooperating therewith to form an upper portion of the wall structure, tubes of some of the panels of the first group of said one path having upper portions interlaced with lower portions of tubes of some of the panels of the second group of said one path, tubes of some of the panels of the first group of said other path having upper portions interlaced with lower portions of tubes of some of the panels of the second group of said other path, means for supplying fluid in parallel flow relation to said paths, means interconnecting the tube panels of the first and second groups of each path so as to provide serial flow of fluid successively through the tube panels of the first group and the tube panels of the second group and so that with respect to the longitudinal edges of the wall structure the general direction of flow of fluid in said one path in either the upper or lower portion of the wall is opposite to the general direction of flow in said other path in the corresponding wall portion.
